US0D1075411S

(12) **United States Design Patent** (10) **Patent No.:** **US D1,075,411 S**
(45) **Date of Patent:** **** May 20, 2025**

(54) **BOTTLE**(71) Applicant: **YETI Coolers, LLC**, Austin, TX (US)(72) Inventors: **Dustin R. Bullock**, Austin, TX (US); **Colin Darling**, Austin, TX (US); **Evan Goldberg**, Austin, TX (US); **Hector Barea**, Austin, TX (US); **Melissa Cosler**, Austin, TX (US)(73) Assignee: **YETI Coolers, LLC**, Austin, TX (US)(***) Term: **15 Years**(21) Appl. No.: **29/857,972**(22) Filed: **Oct. 26, 2022**(51) **LOC (15) Cl.** ..... **07-01**(52) **U.S. Cl.**USPC ..... **D7/510; D7/511**(58) **Field of Classification Search**

(74) *Attorney, Agent, or Firm* — Banner & Witcoff, Ltd.

(57) **CLAIM**

The ornamental design for a bottle as shown and described.

DESCRIPTION

FIG. 1 is a top, front, left perspective view of a bottle showing our new design;

FIG. 2 is a bottom, rear, left side perspective view thereof; FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

1 Claim, 8 Drawing Sheets
